(57) **CLAIM**

I claim the ornamental design for a T-shirt with biceps measurement, as shown and described.

DESCRIPTION

FIG. 1 is a front, top isometric view of a T-shirt with biceps measurement;

FIG. 2 is a front view thereof;

FIG. 3 is a right side view thereof;

FIG. 4 is a rear view thereof;

FIG. 5 is a left side view thereof;

FIG. 6 is a top view thereof; and,

FIG. 7 is a bottom view thereof.

The evenly spaced broken lines shown on the T-shirt with biceps measurement represent stitch lines and are part of the claimed design. The dash-dot-dash-dot broken lines showing a front portion of a neckline forms no part of the claimed design.
